UNITED STATES PATENT OFFICE

FERNAND R. TOURTOIS, OF NEW YORK, N. Y., ASSIGNOR TO COTY, INC., OF NEW YORK,
N. Y., A CORPORATION OF DELAWARE

DESIGN FOR A BOTTLE

Application filed September 1, 1932. Serial No. 44,737. Term of patent 14 years.

To all whom it may concern:

Be it known that I, FERNAND R. TOURTOIS, a citizen of the Republic of France, residing at 128 Fort Washington Avenue, New York city, have invented a new, original, and ornamental Design for Bottles, of which the following is a specification, reference being had to the accompanying drawing, forming a part thereof.

I claim:

The ornamental design for a bottle as shown.

FERNAND R. TOURTOIS.
